Wilson Jones Company, Chicago, Ill., a corporation of Massachusetts

Application July 16, 1953, Serial No. 25,999

Term of patent 14 years

(Cl. D74—1)

To all whom it may concern:

Be it known that I, Herbert W. Marano, a citizen of the United States and a resident of Summit, New Jersey, have invented a new, original, and ornamental Design for a Combined Desk Pad and Pen Holders, of which the following is a specification, reference being had to the accompanying drawing, forming a part hereof, in which:

The disclosure of the pens shown in dotted lines on the drawing is for illustrative purposes only.

I claim:

The ornamental design for a combined desk pad and pen holders, as shown and described.

HERBERT W. MARANO.
